UNITED STATES PATENT OFFICE.

MICHAEL J. O'RIELLEY, OF BUFFALO, NEW YORK, ASSIGNOR OF ONE-FOURTH TO JOHN L. C. CRONYN, OF SAME PLACE.

WATER-CLOSET.

SPECIFICATION forming part of Letters Patent No. 249,391, dated November 8, 1881.

Application filed May 18, 1881. (Model.)

To all whom it may concern:

Be it known that I, MICHAEL J. O'RIELLEY, of the city of Buffalo, in the county of Erie and State of New York, have invented new and 5 useful Improvements in Water-Closets, of which the following is a specification, reference being had to the accompanying drawings.

This invention relates to an improvement in 10 water-closets, whereby a certain quantity of water is discharged from the supply-pipe into the bowl for cleaning the same each time the closet is used, thereby avoiding waste of water, and at the same time avoiding a deficient 15 supply of water.

My invention consists, principally, of the mechanism whereby the requisite quantity of water is automatically discharged into the bowl from the supply-pipe; also, of the mechanism 20 whereby the pan is dumped at the same time that the water is turned on; and of the particular construction of the air-vessel, whereby the operation of the mechanism is regulated; and of the particular construction of the valve 25 which controls the water-supply, as will be hereinafter fully set forth.

In the accompanying drawings, Figure 1 is 30 a front elevation of a water-closet provided with my improvements. Fig. 2 is a fragmentary side elevation thereof. Fig. 3 is a sectional elevation, on an enlarged scale, of the valves and water-passages. Fig. 4 is a sectional elevation of the diaphragm which actuates the water-supply valve and the pan.

35 Like letters of reference refer to like parts in the several figures.

A represents the bowl of a water-closet; B, the pan, hinged at b in the usual manner; C, the receiving-hopper underneath the pan; and 40 D, the seat, hinged at its rear side, all of ordinary and well-known construction.

E represents the water-supply pipe, which is connected with the main pipes or some reservoir in which the water is kept under a suitable pressure.

E' E² are two branches of the supply-pipe E, the branch E' leading to a valve, F, and the branch E² to a valve, G. The valve F is composed of three chambers or passages, f f' f², 45 connected by two valve-seats, g g', the seat g

being arranged between the chambers f and f', and the seat g' between the chambers f' and f². The branch E' of the pipe E connects with the lower chamber, f.

h and h' represent two valves, secured to a 55 vertical rod, H, which extends upward through a stuffing-box in the valve-case, and is connected at its upper end with the seat D at d, and provided at its lower end, preferably within the casing of the valve F, with a spring, i, 60 which tends to hold the valve-rod H and seat D in a raised position. As shown in the drawings, the spring i rests upon a removable cap, I, which is provided with a socket, in which the lower end of the rod H is guided. The 65 valves are so arranged on the rod H that when the upper valve, h', is closed against its seat g', as shown in Fig. 3, the lower valve, h, will be below its seat g and permit the water to pass from the chamber f into the chamber f', 70 and that if the lower valve, h, is raised against its seat the upper valve will be lifted from its seat and permit the water to flow from the chamber f' into the chamber f².

j represents a pipe which extends from the 75 chamber f' of the valve F to the lower part of an air-vessel, J. The latter is preferably cast in one piece with the receiving-hopper C, to save room; but any other suitable construction may be adopted.

l represents a pipe which runs from the upper chamber, f², of the valve to the lower part of a chamber, L, which is provided with a flexible diaphragm, m, of india-rubber or other suitable material.

n is a waste-pipe, which connects the pipe l with the receiving-hopper C, and which is provided with a stop cock or valve, n', whereby the flow of water through this pipe can be regulated. The diaphragm m is connected by a rod, 90 o, with a weighted lever, o', which is pivoted to the side of the receiving-hopper C, and connected by an arm, o², with the pivoted pan B in such manner that the pan is dumped when the lever is raised.

p is a short arm or nose, formed on the lever o', near its fulcrum, for operating the water-supply valve G. This valve is composed of three chambers, q q' q², connected by two valve-seats, r r', which are opened and closed alter- 100

nately by two valves, R R', which are attached to a rod, r^2 . The latter projects through a stuffing-box in the valve-case and bears against the short arm p of the lever o' , with which it 5 is held in contact by a spring, s , which surrounds the outer end of the rod r^2 , within the valve-case. The branch E^2 of the pipe E connects with the chamber q of the valve G, and the chamber q' connects by a pipe, T, with the bowl A.

10 The operation of this mechanism is as follows: Upon a person occupying the seat D the latter and the rod H are depressed, the lower valve, h , is opened and the upper valve, h' , closed, as represented in Fig. 3. The water now passes from the supply-pipe E through the branch E' , chambers f and f' , and pipe j into the vessel J, until the air contained therein is compressed to the same pressure 15 which exists in the supply-pipe E, when the flow of water through these passages ceases. When the person rises from the seat the latter and the valve-rod H are raised by the spring i until the lower valve, h , is closed, when the upper valve, h' , is opened. The water contained in the air-vessel J and pipe j is now 20 expelled under the pressure of the compressed air and passes through chambers f' f^2 and pipe l into the chamber L. The space below the diaphragm in this chamber is filled by the water, and the diaphragm is raised by the water pressing against it. The movement of the diaphragm raises the lever o' , whereby the pan B is dumped and the valve-rod r^2 actuated 25 in such a manner that the valve R is opened and the valve R' closed. The water now passes from the supply-pipe E, through the branch E^2 and the chambers q q' of the valve G, into the pipe T, and thence into the bowl A. At the same 30 time that the water passes from the air-vessel J into the diaphragm-chamber L a portion of the water confined in the air-vessel and pipe j escapes into the hopper C through the pipe n .

35 The quantity of water which escapes through the pipe n in a certain time is regulated by the valve n' . The length of time during which the lever o' and the diaphragm m are kept in a raised position depends upon the length of time during which water must escape through 40 the pipe n , in order to reduce the water-pressure against the diaphragm to a point at which the weight applied to the lever o' will overcome this pressure and return the diaphragm to its lowest position. When this takes place 45 the valve R is closed, and the further discharge of water into the bowl is stopped.

50 When the pressure of water in the supply pipe E is uniform at all times the pipe n is made of a size which causes the closing of the valve R when the desired quantity of water 55 has been discharged into the bowl. When the pressure-pipe E is irregular or not known the

60 pipe n is provided with the valve n' , whereby the outflow of the water is regulated. The chamber q^2 of the valve G becomes filled with 65 air and water, and the air and water contained in this chamber form a cushion which resists the opening of the valve R', and thereby prevents the sudden closing of the valve R.

65 It is obvious that a movable piston may be 70 employed instead of the diaphragm m ; but I prefer the latter, because it operates with less friction.

75 When the apparatus is applied to a hopper-closet the arm o^2 and the pan B are, of course, omitted.

80 I am aware that previous to my invention water has been supplied to a closet by an air-vessel, and that the pan has been dumped by a plunger operated upon by such water, and this I do not claim; nor do I desire to claim 85 in this application the particular construction of the valve G; but

What I claim as my invention is—

1. In a water-closet, the combination, with 85 the bowl A and water-supply pipe E, of an air-vessel, J, a lifting device, L m, a valve, F, operated by the seat, whereby the pipe E is connected with the air-vessel J when the seat is depressed, and the air-vessel connected with the lifting device when the seat is raised, a valve, G, which is actuated by the water-pressure in the lifting device, and a pipe, n, through 90 which the water escapes from the lifting device, substantially as set forth. 95

2. The combination, in a water-closet, of a bowl, A, water-supply pipe E, valve F, provided with two valve disks and seats, opened or closed alternately, air-vessel J, connected with the chamber f' , lifting device L m, connected with the chamber f^2 , water-escape pipe n, lever o' , actuated by the lifting device and connected with the valve G, the latter being interposed between the water-supply E and the bowl A, and the seat D, whereby the valve 100 F is operated, substantially as set forth. 105

3. In a water-closet, the combination, with a lifting device, L m, of the pipe n and stop-cock n' , whereby the escape of water from the lifting device is regulated, substantially as set 110 forth.

4. In a water-closet, the lifting device composed of a chamber, L, and a flexible diaphragm, m, in combination with the lever o' and valve G, substantially as shown and described. 115

5. The air-vessel J, arranged against the lower contracted portion of the receiving-hopper C and cast in one piece therewith, substantially as shown and described.
